ADOLF KUNZ, OF LEIPSIC-PLAGWITZ, GERMANY.

STEAM-TURBINE.

No. 796,336.

Specification of Letters Patent.

Patented Aug. 1, 1905.

Application filed June 16, 1904. Serial No. 212,841.

To all whom it may concern:

Be it known that I, ADOLF KUNZ, a subject of the Emperor of Germany, residing at Leipsic-Plagwitz, Germany, have invented new and useful Improvements in Steam and Gas Turbines, of which the following is a specification.

In the familiar steam-turbines—as, for example, the Parson turbine—wheels of increasing diameter are employed for utilizing the diminishing steam tension or pressure. This materially increases the difficulty of manufacture, because it is impossible to construct so many patterns or models that each steam-pressure can be adequately taken into account. Moreover, the use of continually larger wheels in itself involves difficulties of manufacture not easily overcome. These objections are to be avoided, according to this invention, by constructing the directrices and the wheels of single-step turbines in the form of flat disks of equal dimension and equal make and arranging them alongside one another, so that each chamber contains but one step. The passage for the steam through the chambers, however, is to be increased by mere addition of equal or uniform wheels according to the diminishing steam-pressure.

This invention is illustrated in the annexed drawings, in which—

Figure 1 is a longitudinal section of a turbine of the kind under consideration. Fig. 2 is a cross-section of the same. Fig. 3 is a view similar to Fig. 1, enlarged and partly broken away. Fig. 4 is a transverse section of Fig. 3, exposing the face of an intermediate disk.

The example of steam-turbine illustrated shows a radial turbine. It consists of a number of disks A, arranged one behind the other on a common shaft. In the example shown instead of blades, as common in steam-turbines, channels B of slight depth are formed in the disks in suitable manner, as by stamping, etching, milling, or otherwise. The several turbine-wheels could, however, be also formed in the customary way by applying blades to the disks.

Having regard to the amount of steam supplied for the work, a number of turbine-wheels A are arranged side by side and the steam led thereto. The steam can be supplied by means of director-channels of any desired kind. It will be well to form the same as ring-shaped director-disks C, corresponding to the movable disks A and similarly formed. The supply of steam is to be radial and the

director-disks C to lie concentric to the turbine-wheels A.

According to the diminishing steam tension the passage for the steam in each chamber 1 2 3, and so on in the turbine shown is to be increased by the addition of like wheels A, so that if, for example, the first chamber 1 comprises four wheels A the following chambers can be provided with wheels to the number of five, six, and more. The more gradually that the number of wheels alongside one another increases and the flatter these wheels are the more accurate an allowance or provision can be made for the diminishing steam tension.

The steam which, for example, is led to turbine-wheels A of chamber 1 through the conducting arrangement C of such chamber must now, after doing its work therein, be led to the conducting portion of chamber 2. The delivery of steam is also likewise continued for all succeeding chambers 3 4 5, and so on. This is accomplished in the example shown by separating the various turbine-chambers 1 2 3 by steam-transfer channels or channel-pieces. These latter consist of two parts—the circular disk D, of equal diameter with the turbine-wheels A, and the ring-shaped disk E, corresponding to the director-disks C. The intermediate disks D, with the turbine-wheels A, are arranged on the shaft F of the turbine, while the intermediate rings E, with director-disks C, are fitted into the housing G of the turbine. The intermediate disks D thus take part in the rotation of the turbine-shaft F, while the intermediate rings E do not partake of motion. Both parts D and E of the steam-conducting channels must as far as possible make closure against one another. It is, however, not difficult to fit them steam-tight to one another, as their walls can be made of sufficient thickness.

In the example shown a head or confining-disk H is mounted on the shaft F, against which the turbine-wheels A of the first chamber are arranged, whereupon a steam-transfer channel D is slipped onto the shaft F. In like manner the turbine-wheels of the succeeding chambers and the transfer-channels D are arranged on the shaft F. In the example shown the first chamber 1 contains four turbine-wheels A the second chamber five, the third chamber six, the fourth chamber seven, and the fifth chamber eight. After the last intermediate disk D is in place all the disks on shaft F are pressed together by

the end disk J. A nut K or other means can be employed for this purpose. In like manner is effected the assemblage of the directrix or blades C and intermediate rings E, and this director-blade arrangement is likewise compressed by means of a closing-ring L. The steam entering at inlet M passes first through the directrix-blade apparatus C of the first chamber and entering the turbine-wheels A of this chamber imparts rotation thereto. The steam here utilized passes through openings N of turbine-wheels A of the first chamber into the intermediate disk D and flows through its channels into those of the intermediate rings E, whence it is led to the directrix-blade apparatus of the next chamber. In like manner the steam passes from one chamber to the other.

If the turbine-wheels A are shaped as flat movable disks with flat channels formed by milling, pressing, or otherwise, all being of equal width and equal diameter, they can be easily and cheaply produced on a manufacturing scale or basis. With the aid of a number of equal disks of this kind it is also possible by simple juxtaposition to construct turbines of increasing efficiency without having to increase the diameter of the turbines. The elongation in axial direction is of small moment in the present class of turbines, because all disk-like turbine-wheels A, with intermediate disks D, can be secured close to one another on a common shaft, so that they form with the same a single rotating body of considerable rigidity. Notwithstanding required lengthening of the turbine in axial direction the shaft or axle itself is not disadvantageously loaded, but rather so stiffened into one body by the entire structure that it cannot bend or distort.

Such turbines can be utilized as well for steam as also for air or some desired gas. The pressure or motive agent being suitably passed through successive chambers will act in each.

The directrices and wheels are shown in Fig. 4 on an enlarged scale with their ribs O and P.

What I claim as my invention, and desire to secure by Letters Patent, is—

1. A single-step turbine in which the steam passes radially through the blades comprising turbine-chambers for utilizing the diminishing steam or other pressure, and a group of turbine-wheels in each of said chambers, the number of disks for each group increasing in the direction of the flow of the motive agent, said wheels being composed of flat disks of like dimension and like construction.

2. A single-step radial turbine comprising chambers, turbine-wheels of increasing number in the successive chambers, and ring-shaped directrix-wheels C of like form and dimension.

3. A turbine comprising chambers, wheels grouped in increasing number in the chambers, directrix-wheels for the first-named wheels, and intermediate disks D arranged between the chambers and provided with transmission-channels for the pressure or steam.

4. A turbine comprising chambers, turbine-wheels of increasing number in the chambers, ring-shaped directrix-wheels for the turbine-wheels, and intermediate disks E between the directrix-wheels and provided with transmission-channels for the steam or pressure.

5. A turbine comprising chambers with a shaft, rotary turbine-wheels of increasing number in the chambers and mounted on the shaft, intermediate disks having transmission-channels also mounted on the shaft and made to rotate with the turbine-wheels, directrix-disks for the turbine-wheels, and non-rotary intermediate rings or disks E fitted into the chambers and having transmission-channels made to coact with the channels of the disks on the shaft.

In testimony whereof I have hereunto set my hand in the presence of two subscribing witnesses.

ADOLF KUNZ.
